UNITED STATES PATENT OFFICE

108,311

DESIGN FOR A COMBINATION DRESS

Oscar Zaretzky, New York, N. Y.

Application December 11, 1937, Serial No. 73,536

Term of patent 3½ years

To all whom it may concern:

Be it known that I, Oscar Zaretzky, a citizen of the United States of America, and resident of the county of Bronx, city and State of New York, have invented a new, original, and ornamental Design for a Combination Dress, of which the following is a specification, reference being had to the accompanying drawing forming a part thereof.

In the drawing:

Figure 1 is a front view of a combination dress embodying my new design and showing a gilet attached thereto.

Figure 2 is a back view of the combination dress.

Figure 3 is a front view of the gilet itself.

The characteristic feature of my design resides in the combination on the dress disclosed of the specific gilet which is attached to the dress at the waist and shoulder portions as shown.

I claim:

The ornamental design for a combination dress substantially as shown and described.

OSCAR ZARETZKY.
